UNITED STATES PATENT OFFICE

WILLIAM C. A. HENRY, OF COLUMBUS, OHIO.

STOKER MECHANISM.

1,134,198.

Specification of Letters Patent.

Patented Apr. 6, 1915.

Application filed July 21, 1913. Serial No. 780,160.

To all whom it may concern:

Be it known that I, WILLIAM C. A. HENRY, a citizen of the United States, residing at Columbus, in the county of Franklin and State of Ohio, have invented certain new and useful Improvements in Stoker Mechanism, of which the following is a specification.

The invention relates to automatic stoker mechanism and has for its primary objects, the provision of an arrangement whereby the packing of the coal under the plungers is avoided; the provision of means to prevent packing of the coal in the bearings through which the plungers work; and the provision of improved means for applying the power to reciprocate the plungers whereby binding and undue friction is eliminated. Certain embodiments of the invention are illustrated in the accompanying drawings, wherein—

Figure 1 is a longitudinal section through a feed trough of an underfeed stoker embodying the invention, Figs. 2 and 3 are sections on the lines II—II and III—III respectively of Fig. 1, Fig. 4 is a longitudinal section through a modified construction, and Fig. 5 is a section on the line of V—V of Fig. 4.

Referring to the drawings, 1 is the underfeed trough of a furnace, the side gates not being shown; 2 is the main feed piston at the rear end of the trough, which is reciprocated by any desired means; 3, 4, and 5, are secondary feed plungers working through the bottom of the trough and provided with an agitator 6; 7 is a rock shaft operated from power means, and provided with a crank 8 for operating the secondary plungers, and 9 is one of a pair of bars lying on opposite sides of the crank 8 and connected at their front ends with the secondary plunger, by means of the transverse bolts 10.

The rear secondary plunger 3 is guided in two bearings 11 and 12, the bearing 11 being located at the point at which the plunger enters the trough through the bottom thereof, and the bearing 12 being placed to the rear of the bearing 11. The two connecting rods of course straddle the bearing 12. The bearings are all provided with bushings which are held in place by means of the set screws 13 (Fig. 2) held in position by means of the nut locks illustrated.

The secondary plunger 4 is also operated from the connecting rods 9, such connecting

rods being extended downward as indicated at 14. The pair of connecting rods 15 are connected at their rear ends to the downwardly projecting portion 14, by means of a transverse bolt or rod 16, and are connected at their forward ends to the plunger 4 by means of the bolt 17. This plunger 4 is supported in a pair of bearings 18 and 19, and the connecting rods 15 straddle the rear bearing 19 and the plunger itself.

The forward secondary plunger 5 is guided in a pair of bearings 20 and 21, and is operated by a pair of connecting rods 22 secured at their rear ends to the downwardly projecting portions 14, by the bolt 14', and at their front ends pivoted to the rear end of the plunger by means of the bolt 23.

It will be noted that each of the plungers 3, 4, and 5 is guided in a pair of bearings 75 spaced apart, and that the front bearing in each case is relatively short. This is an advantageous construction, in that any coal which works into the front bearing from the trough easily works through and escapes 80 from the rear side of the bearing, whereas with a single long bearing the coal would be much more apt to collect in the bearing and cause a large amount of friction. It will also be noted that this arrangement of 85 bearings spaced apart permits the actuation of the plungers by connections attached intermediate the two bearings. This reduces the binding and friction which is present where a single long bearing is used with the 90 driving connection to the rear of such bearing. This tendency to bind is of course due to the fact that the application of power from the connecting rod to the plungers 95 is not exact in alinement with the direction of movement of the plungers, but is in some positions of the connecting rods applied at an angle, causing binding and undue wear at the ends of the bearing. With 100 two separated bearings such as those illustrated with the application of power therebetween this tendency to bind is substantially eliminated. It will also be noted that insofar as the plungers 4 and 5 are concerned the application of power from the 105 depending portions 14 is always exactly in alinement with the path of movement of the plungers, since the rear plunger 3 acts as a guide for the portions 14, so that any tendency toward movement at right angles 110 to the path of movement of the plungers 4 and 5 is eliminated. The rear plunger 3

therefore acts as a guide or cross head for the plungers 4 and 5, and frictional losses are thus avoided.

With secondary plungers such as those illustrated there is a tendency of the fine coal to pack between the bottom sides of the plungers and the bottom of the trough, and in many cases the driving mechanism of the stoker is stalled incident to the friction at these points. In order to relieve this condition I have provided the slots 24 under each secondary plunger. These slots are always covered by the plungers, so that there is no loss of coal due to them, but when the fine coal or dust works back to these points beneath the plungers it is free to drop out, instead of collecting and packing. The portions of the bottom of the trough in advance of the slots are cleaned by the plungers themselves, since the plungers ride back a sufficient distance to uncover the portions of the bottom in front of the slots. By the use of these slots substantially all friction incident to the collection and packing of the fine coal is eliminated, and the plungers work freely at all times.

Figs. 4 and 5 illustrate the application of the slotting principle just described, to a modified type of plunger or agitating means. In this construction of Figs. 4 and 5 there is only a single plunger 25 working on the bottom of the trough 26, such plunger being provided with a plurality of upstanding agitators 27. The plurality of slots 28 in the bottom of the trough beneath the plunger prevent any packing of the coal, as the fine coal which would otherwise collect and pack drops through the bottom.

What I claim is:

1. In combination with a feed trough, a plunger inclined with respect to the trough and working through the bottom thereof, a bearing for the plunger where it passes through the bottom of the trough, a second bearing for the plunger spaced to the rear of the other bearing, means for operating the plunger secured thereto intermediate the two bearings, a second plunger in advance of the first mentioned plunger, and a connection from said first mentioned plunger intermediate the two bearings for operating the said second plunger. 40 45 50

2. In combination with a feed trough, a plunger inclined with respect to the trough and working through the bottom thereof, a bearing for the plunger where it passes through the bottom of the trough, a second bearing for the plunger spaced to the rear of the other bearing, a connecting rod pivoted to the plunger intermediate the two 60 bearings and having a downward extension, means for operating the connecting rod, a second plunger in advance of the first plunger and also working through the bottom of the trough, and a connecting rod for operating said second plunger, said connecting rod being pivoted at one end to said second plunger and at the other end being pivoted to the said downward extension. 65

In testimony whereof I have hereunto signed my name in the presence of the two 70 subscribed witnesses.

WILLIAM C. A. HENRY.
